UNITED STATES PATENT OFFICE.

HENRY JENKINS, OF GILLETTE, WYOMING.

MAIL-BAG CATCHER AND DELIVERER.

1,084,579.

Specification of Letters Patent. Patented Jan. 13, 1914.

Application filed May 14, 1912. Serial No. 697,252.

To all whom it may concern:

Be it known that I, HENRY JENKINS, a citizen of the United States, residing at Gillette, in the county of Crook and State of Wyoming, have invented new and useful Improvements in Mail-Bag Catchers and Deliverers, of which the following is a specification.

This invention relates to mail bag catching and delivering devices wherein means are provided for receiving a mail bag carried by a moving vehicle such as a train, and the moving vehicle carrying means for receiving a mail bag from the first mentioned means.

An object of this invention is to provide a device of the above mentioned character which is durable, efficient and of such construction as to prevent the tearing or wear- ing of the bag.

A further object of the invention is to provide a mail bag catching and delivering device which consists of but a few simple parts whereby it may be manufactured and placed upon the market at a very small cost.

With the above and other objects in view my invention consists in such details of construction and in the arrangement and combination of parts as will be hereinafter more fully described and specifically pointed out in the appended claims.

In describing my invention in detail reference will be had to the accompanying drawings wherein like characters denote like or corresponding parts throughout the several views, and in which;

Figure 1 is a side elevation of my invention shown applied to a train and a stationary post. Fig. 2 is a plan view of one of the grabbing arms. Fig. 3 is a detailed view, and Fig. 4 is another detailed view.

The base portion 1 together with the upright post 2 constitute the supporting structure for the stationary apparatus. The post 2 is provided with the collars 4 which are spaced apart thereon, the said collars being provided with sleeves 5 for supporting a vertically extending rod 6. A pair of arms as shown at 7 are revolvably mounted upon the rod and near its upper end and are secured together by the base rod 7 and held in position through the medium of the tension spring 9. The ends of the arms are curved as shown at 10 and have secured thereto leaf springs 11 whereby they may receive the eyelets 12 which are carried by the upper

and lower ends of an ordinary mail bag such as shown at 13. A third arm 14 is provided upon the rod which arm is supported intermediate of its ends through the medium of a reinforcing member 15 and held in a certain position through the medium of a coil spring 16. The arm 14 has its forward end bifurcated as shown at 17 whereby it may receive the ends of the leaf springs 18 and rings 19 are carried by the same for the purpose of holding said leaf springs in place thereto. The springs have their ends flared as shown at 20 and are normally held out of engagement with each other through the medium of an expansion spring 21.

The structure carried by the moving vehicle is similar to the one supported by the post 2, however the car is provided with cut-out portions 22 for the reception of the arms 7 and 14 and are provided with pivoted hooks 23 whereby said arms are held in place thereby eliminating the use of the coil springs mentioned in connection with the other structure. In a structure which is carried by the train the arm 14 which carries the grabbing members is disposed before the bag as supporting members as is shown. It is readily obvious that the grabbing arm which is carried by the stationary structure will engage the bag which is carried by the moving structure and that the grabbing arm of the moving structure will engage the bag supported by the stationary structure. By this arrangement it will be seen that a bag is delivered from the train and one received thereto.

The greatest of stress is laid upon the simplicity of my invention and it is thought that the advantages and novel features of the same will be readily appreciated, from the foregoing disclosure.

I desire it to be understood that I may make slight changes in the construction and in the arrangement and combination of parts provided such changes fall within the scope of the subjoined claims.

I claim—

1. In combination with a base plate and a vertically extending post of collars carried by said post, sleeves provided upon said collars, a vertically extending rod adapted to be received by each of said sleeves, a pair of arms supported by said vertically extending rod and near its upper end, said pair of arms adapted to support a mail bag, a third arm mounted upon said rod and below said first

- 2 mentioned arms, said third arm being provided with grabbing members for the purpose described.
2. In combination with a base plate and a post extending therefrom, of collars carried by said post, said collars being provided with sleeves, arms extending horizontally from said rod, means connecting said arms together, clasps upon the forward extremities of said arms for supporting a mail bag, a third arm mounted upon said rod and below said first mentioned arms, a coil spring in engagement with said last mentioned arm and said post, said last mentioned arm being provided with grabbing arms for the purpose described.
3. In combination with a base plate and a post extending therefrom, of collars carried by said post, sleeves provided upon said collars for the reception of a vertically extending rod, a pair of arms carried by said rod and near its upper end, means connecting said arms together, the ends of said arms adapted to be curved and provided with leaf springs whereby they may receive a mail bag, a coil spring in engagement with the lower end of said arms and said post, a third arm upon said rod, a brace rod connected to said arm intermediate its ends and said rod, a coil spring in engagement with said last mentioned arm and said post and grabbing arms carried by said last mentioned arm for the purpose described.
4. In combination with a base plate and a post extending therefrom, of collars carried by said post, said collars provided with sleeves for the reception of a vertically extending rod, a pair of arms upon said rod, means connecting said arms together intermediate of their ends, a coil spring in engagement with the lower of said arms and said post, clasps formed upon the outer extremities of said arms for the reception of a mail bag, a third arm provided upon said rod, a coil spring connecting said last named arm and said post, a brace rod connected to said arm and to said rod, the ends of said last mentioned arm being bifurcated to receive the inner extremities of a pair of leaf springs and means for holding the outer extremities of said leaf springs normally out of engagement with each other for the purpose described.
5. In combination with a base plate and a post extending therefrom, of collars carried by said post, sleeves provided upon said collars for the reception of a vertically extending rod, a pair of arms upon said rod and near its upper end, elastic means connecting the lower of said arms and said post, the outer extremities of said arms adapted to be bent, said arms provided with leaf springs in engagement with said curved extremities whereby clasps are formed for the reception of eyelets carried by a mail bag, a third arm carried by said outer rod and below said first mentioned arm, elastic means connecting said last mentioned arm and said post, a brace rod connecting said last named arm and said first mentioned rod, the outer extremity of said last mentioned rod adapted to receive the inner extremities of a pair of leaf springs, rings upon said last mentioned rod for holding said leaf springs in place and an expansion spring for normally holding the outer extremities of said leaf springs out of engagement with each other for the purpose described.
6. A mail bag receiving and delivering mechanism consisting of two arms supported by a stationary post, the outer ends of said arms provided with clasps adapted to engage the rings of an ordinary mail bag, a third arm carried by said post and having grabbing means on its outer end, said grabbing means consisting of two leaf springs which are connected to said arm, a coil spring disposed between said leaf springs and normally holding their outer free ends apart.
7. A mail bag receiving and delivering mechanism consisting of two arms supported by a stationary post, the outer ends of said arms provided with clasps adapted to engage the rings of an ordinary mail bag, a third arm carried by said post and having grabbing means on its outer end, said grabbing means consisting of two leaf springs which are connected to said rod, a coil spring disposed between said leaf springs and normally holding their outer free ends apart, coil springs connected to said arms and said stationary post for holding said arms in their normal position.

HENRY JENKINS.
